[57] ABSTRACT

A manually operated cymbal spinner is provided with a handle, an arm fixed to and extending generally radially outwardly from the handle, means mounted at the outer end of the arm for fixedly securing the cymbal to the arm, and a rotatable sleeve mounted on the handle; the sleeve to be held by an operator when the cymbal is being spun. In a preferred embodiment the arm is fixed near the top of the handle and extends outwardly at a downwardly extending obtuse angle slightly greater than 90°.

1
CYMBAL SPINNER

BACKGROUND OF THE INVENTION

It is the custom for musical bands to enhance their entertainment potential with various displays — colorful uniforms; intricate maneuvers; baton twirling, high stepping drum majors; and the like. Although percussion devices have received their share of attention, improvements have generally been in the field of controlled sound effects and convenience of use rather than in the field of visual effects.

Gladstone in U.S. Pat. No. 1,647,795 for example, described a cymbal operating device in which cymbals are held in a pair of pivoted handles in a manner such that a portion of each of two cymbals are in direct contact with each other and a "hollow sound" is produced by bringing the balance of the cymbal's areas into contact. In British Pat. No. 222,802 (1924) there is described a foot operated device which moves a single cymbal into an active or into an inactive position relative to a beater head.

In the field of "spinning" Harrold et al. in U.S. Pat. No. 2,812,683, describes a baton with a swivelly attached handle which permits of the spinning of the baton at a rapid speed without a high degree of skill on the part of the user.

SUMMARY OF THE INVENTION

The present invention is directed to a cymbal spinner, the latter permitting, by a slight movement of the wrist of the cymbal player, a cymbal to spin rapidly around a handle making for a flashing visual display. Such display can be used to highlight field presentations by a band. The cymbal spinning device of the invention comprises: (a) a handle, (b) an arm fixed to and extending generally radially outwardly from the handle, (c) means mounted at the outer end of the arm for fixedly securing the cymbal thereto, and (d) a sleeve member rotatably mounted on a portion of the handle and adapted to be held manually by an operator when the cymbal is being spun. In a preferred embodiment, the sleeve envelopes substantially all the handle below the arm and the arm is fixed near the upper end of the handle and forms therewith a downwardly extending obtuse angle slightly larger than 90°.

DESCRIPTION OF THE DRAWINGS

FIG. 1 is a perspective view of a cymbal provided with the cymbal spinner of the invention;

FIG. 2 is a cross sectional view of a preferred embodiment of the cymbal spinner of the invention; and

FIG. 3 is a cross sectional view of the device of FIG. 2 in a slightly modified form.

DESCRIPTION OF THE PREFERRED EMBODIMENT

Referring to the drawings, a cylindrical handle 10 is provided with a rotatable sleeve 12. The sleeve 12 is held on the handle 10 by a washer 14 and a screw 16.

An arm 18 is secured by threads 20 near the top of handle 10 and extends generally radially outwardly, but slightly angularly upwardly, to form a downwardly extending angle slightly greater than 90° (see FIG. 2). The terms "top", "down" and "downwardly", as used

2

herein, refer to directions in the structure as shown in the drawings which is the same position in which an operator holds the handle 10 in normal use. The downwardly extending angle made by the arm 18 with the handle 10 is made slightly more than 90°, for example about 100°, in order to provide clearance between the spinning cymbals and the hands and arms of the operator. If said angle is too small the cymbals may strike the operator's arms and if said angle is too large the cymbals will be in an awkward position when being struck against each other in the usual manner.

The outer end of the arm 18 is provided with a threaded portion 22 over which is positioned the cymbal 24 between plastic or fiber washers 26, 28; the latter positioned between metal washers 30, 32. The washer-cymbal assembly is held on the threaded portion 22 by nut 34.

The arm 18 can be held more rigidly in handle 10 by use of a screw 36 (FIG. 3) extending axially down from the top of the handle 10 to bear against arm threaded portion 20. It will be apparent, however, that arm 18 can be fixed in handle 10 by any suitable means, such as by a press fit, for example; or handle 12 and arm 18 can be made as a unitary structure.

DESCRIPTION OF OPERATION

In normal use of the cymbals, that is, to strike them against each other; the operator grasps the handle 10 in a manner such that his thumb and forefinger press against, or are partly wrapped around, the arm 18. This prevents the handle 10 from rotating relative to the sleeve 12. When spinning the cymbal, the operator grasps only the sleeve 12 and maintains the spin by a slight movement of his wrist. Spinning is most easily accomplished by holding the cymbals aloft for the reason that straightening the arms upwardly minimizes the possibility of contact between a cymbal and the operator's arm.

It will be apparent to one skilled in the art to which the invention pertains that various changes and modifications may be made therein without departing from the spirit of the invention or the scope of the appended claims.

I claim:

1. A cymbal spinning device comprising: (a) a handle, (b) an arm fixed to and extending generally radially outwardly from said handle, (c) means mounted at the outer end of said arm for fixedly securing a cymbal thereto, and (d) a sleeve member rotatably mounted on a portion of said handle and adapted to be held manually by an operator when said cymbal is being spun.

2. The device according to claim 1 wherein said arm is fixed near the upper end of said handle and said sleeve envelopes substantially all said handle below said arm.

3. The device according to claim 1 wherein said arm forms with said handle a downwardly extending obtuse angle slightly larger than 90°.

4. The device according to claim 1 wherein said arm is fixed near the upper end of said handle and forms therewith a downwardly extending obtuse angle slightly larger than 90°, and wherein said sleeve envelopes substantially all said handle below said arm.

UNITED STATES PATENT OFFICE
CERTIFICATE OF CORRECTION

Patent No. 3,710,669 Dated January 16, 1973

Inventor(s) Russell Jones

It is certified that error appears in the above-identified patent and that said Letters Patent are hereby corrected as shown below:

Column 1, line 5, after "various", insert --visual--.

Column 2, line 40, delete "nd" and insert --and--.

Signed and sealed this 13th day of November 1973.
